UNITED STATES PATENT OFFICE.

HERMANN SUNDHAUSSEN, OF ESSEN, GERMANY, ASSIGNOR TO FRIED. KRUPP AKTIENGESELLSCHAFT, OF ESSEN-ON-THE-RUHR, GERMANY.

DISK-SHAPED COMMUTATOR FOR GYROSCOPE-MOTORS.

1,398,404.

Specification of Letters Patent. Patented Nov. 29, 1921.

Application filed January 15, 1921. Serial No. 437,604.

To all whom it may concern:

Be it known that I, HERMANN SUNDHAUSSEN, residing at Essen, Germany, a citizen of the German Republic, have invented a certain new and useful Improvement in Disk-Shaped Commutators for Gyroscope-Motors, (for which I have filed an application in Germany November 11, 1918), of which the following is a specification.

10 This invention relates to disk-shaped commutators for gyroscope motors and has for its object to produce a commutator of this type which will possess a long life even when the number of revolutions executed by the 15 gyroscope motor is very high and, as a result, the commutator sectors are subjected to a heavy wear, and thereby enabling a satisfactory working of the gyroscope motor to be secured which will not be disturbed either 20 by the formation of sparks nor by variations in the number of revolutions.

In the drawing affixed to this specification and, forming part thereof, a disk-shaped commutator designed for a continuous current gyroscope motor having a vertical axis and embodying the invention is illustrated together with parts of the appropriate motor armature, by way of example. In the drawing—

30 Figure 1 is a vertical section through the commutator, and

Fig. 2 is a top view.

Referring to this drawing, each sector of the commutator comprises two elements A 35 and B interconnected by means of screws C, of which the upper element, A, serves as the bearing surface for the armature brushes D, and which hereinafter is designated the "sliding sector," whereas the lower element, B, 40 which is designed to establish the connection with the armature winding and supports the appropriate sliding sector A is hereinafter indicated as the "supporting sector."

The supporting sectors B are made in the 45 form of ring sectors as shown in Fig. 2 and are inserted, with the interposition of non-conductive material, in an annular depression formed in a disk-shaped element E¹ which for its part is rigidly connected to the 50 armature body forming the gyrating mass of the gyroscope, and which encircles the armature shaft e² after the manner of a hub. The supporting sectors B are secured against radial displacement by a pressing ring G 55 tightly embracing the supporting sectors B

on the outside and bearing up against a circular ledge e³ which limits the depression formed in the disk E¹, a layer of non-conducting material being arranged between the sectors B and the ring G. In addition, 60 the supporting sectors B and therewith the sliding sectors A screwed down on them are secured, against any liability of those of their portions disposed close to the axis of rotation of the motor being lifted off from their base due to the action of centrifugal force, by a ring K screwed upon the hub-shaped portion of the disk E¹, and which ring with its lower face resting on ledge b¹, is provided to hold each sector B, down 65 upon its base. Between the ring K and the supporting sectors B there is interposed a ring F of non-conducting material. Into the upper face of each supporting sector B there is tooled a rectangular, radially disposed groove b² (Fig. 2) into which the respective sliding sectors A are inserted. The ends a¹ of the sliding sectors A facing the axis of rotation of the gyroscope motor extend unsupported beyond the two rings F 70 and K forming the internal elements of the fastening means for the supporting sectors B and cover them, while those parts of the upper surface of said ends a¹ contiguous to the axis of rotation form the bearing surface for the brushes D. These unsupported ends a¹ are moreover tapered wedgewise to such an extent that the vertical side faces of each entire commutator sector comprising a sliding sector A and a supporting sector B, will be located in one and the same vertical plane. The gaps between the side faces of the sectors B disposed with a slight space apart from and in parallel to, each other, are filled with a non-conducting material. The sliding sectors A are secured 75 against any undesirable centrifugal action by a removable steel ring H tightly embracing a ring J of a non-conducting material 80 which ring J bears up with its inside face 90 against the sliding sectors A and the outer, stepped portions of the supporting sectors B. Besides this, the ring H engages, by means of a ledge h¹ arranged on its underside, a ledge g¹ appertaining to the steel 95 ring G, said ring H thus contributing to secure the supporting sectors B against any objectionable action of centrifugal force.

By fastening the commutator sectors and arranging the parts as described hereinbe- 110

fore a commutator is produced which is strong and durable, easy to repair and which is furthermore unaffected by the formation of sparks or by variations in speed.

5 The extraordinary long life of the improved commutator is due to the fact that the sliding surface for the brushes is located in direct vicinity of the axis of rotation of the gyroscope motor. For by these means, on 10 the one hand, the peripheral velocity of two portions of the sliding sectors A with which the brushes D make contact is reduced to a minimum, so that even in the case of the gyroscope motor working at a very high 15 speed, the frictional and accordingly the mechanical wear of the parts will be comparatively low. On the other hand, the vibratory motions about its horizontal central position, of the sliding surface for the 20 brushes is located in the immediate vicinity of the axis of rotation of the motor, which motions are provoked by the high number of rotations of the gyroscope body, will be less than in the case of a sliding surface arranged 25 at a greater distance remote from the axis of rotation. Hence, the resilient brush holders (not shown) are enabled in this case to more securely maintain the brushes in a position which will warrant a good contact, 30 when such vibratory motions take place. But owing to the fact that the brushes constantly bear up with their full face against the sliding surface, there exists absolute security that the formation of sparks is obviated, which would tend to deteriorate the 35 friction between the brushes and the sliding surface, and thus reduce the number of revolutions of the gyroscope motor to an objectionable degree and moreover quickly wear 40 down the sliding sectors A. Careful long-run tests undertaken to this end have shown that with the extremely high number of revolutions at which gyroscope motors of the type specified are operated, a sliding 45 surface having a diameter twice as large as that made in accordance with the present construction and such as was customarily provided for commutator sectors of the old type, resulted in considerable variations of 50 the number of revolutions and such a strong formation of sparks that the commutator sectors had to be replaced after working periods which were from five to seven times shorter than the working periods secured by 55 aid of the hereinbefore-described commutator sectors which work entirely without spark formation or variations of speed. The advantage that only short working intervals are required is due to the fact that 60 in order to remove any sliding sectors A which may happen to be worn down, all that need be done is to slacken the screws C whereupon the sliding sectors A may be conveniently removed from the grooves b², 65 while a disconnection and removal of the

rings forming the means to prevent any undesirable centrifugal action is not required. Besides this, the ring K which forces the supporting sectors B down on their base, at the same time serves to prevent 70 any tilting of the commutator sectors A and B on the edge g² (Fig. 1) of the ring G and therewith a lifting, if but only to a very slight extent, of the portions of the sectors A B adjoining the axis of rotation of the 75 motor, and this despite the fact that the point of application of the centrifugal force lies, about, on a level with the upper end plane of the circular ledge g¹ of the pressing ring G. By these means there is prevented 80 an increase of the pressure existing between the brushes D and their sliding surface, and thus an increase of friction liable to augment the wear of the sliding sectors A and to reduce the number of revolutions of the 85 motor to an objectionable extent.

Claims.

1. A disk-shaped commutator of the class described comprising a supporting element, a multiplicity of supporting sectors 90 mounted thereon, a corresponding number of sliding sectors secured to said supporting sectors, means for securing said supporting sectors to said supporting element so that said sliding sectors may be removed without disconnecting said securing means.

2. A disk-shaped commutator for motors of the class described comprising a supporting disk-shaped element provided with a hub portion, supporting sectors mounted 100 upon said supporting element, each of said supporting sectors being provided with a ledge portion disposed adjacent the hub of said supporting element, sliding sectors secured to said supporting sector, a ring 105 screwed upon said hub and abutting said supporting sectors on said ledges, securing rings for retaining said sectors in place, said sliding sectors being removable without disconnecting said securing rings.

3. A disk-shaped commutator for motors of the class described comprising a recessed disk-shaped supporting element, said supporting element being provided with a hub portion, a multiplicity of supporting sectors mounted on said supporting element, said supporting sectors being cut away to form ledges which are disposed adjacent said hub portion, a securing member screw-threadedly engaging said hub portion and contacting said supporting sectors on said ledges, sliding sectors removably secured to said supporting sectors, said sliding sectors being disposed so that their ends face the axis of rotation of the motor, the ends 115 of said sliding sectors being adapted to contact with the brushes, and securing elements for retaining said sectors in position upon said supporting element.

4. A disk-shaped commutator for motors 130

of the class described comprising a supporting element, supporting sectors mounted on said supporting element, a securing ring engaging said supporting element and supporting sectors for holding said supporting sectors in place, sliding sectors secured to said supporting sectors, said sliding sectors being provided with freely extending ends which face the axis of rotation of the motor, 10 said ends covering said securing ring.

5. A disk-shaped commutator of the class described in combination with a motor comprising a supporting element provided with a hub portion, a multiplicity of supporting 15 sectors mounted thereon, each sector being shaped to form a ledge disposed adjacent said hub portion, sliding sectors removably

secured to said supporting sectors, a ring screw-threadedly engaging said hub and bearing upon the ledges formed on said supporting sectors to prevent vertical displacement due to centrifugal action, a pressure ring abutting the outer ends of said supporting sectors and said supporting element and additional rings engaging said sectors to 25 prevent any radial displacement thereof.

The foregoing specification signed at Essen, Germany, this 9th day of December, 1920.

HERMANN SUNDHAUSSEN.
